UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,272,282.

Specification of Letters Patent.

Patented July 9, 1918.

Application filed November 20, 1917. Serial No. 202,934.

To all whom it may concern:

Be it known that I, JAMES L. MCQUARRIE, a citizen of the United States, residing at Montclair, in the county of Essex and State 5 of New Jersey, have invented certain new and useful Improvements in Telephone-Exchange Systems, of which the following is a full, clear, concise, and exact description.

10 This invention relates to automatic switches, and more particularly to automatic switches of the type used in telephone exchange systems.

15 This invention is an improvement upon applicant's copending application, Serial No. 158,567, filed March 30, 1917.

20 It is the object of this invention to provide a switch which shall be mechanically simple, and also compact and low in cost of construction.

25 A feature of the present invention is the use of a contact bank of the panel type in connection with a switch of the well-known "up and around" structure. The contact banks are essentially similar to those used and described in the above mentioned application, excepting that each shelf of contacts is provided with multiple contacts on its lower surface as well as on its upper surface.

30 It is obvious that by this arrangement, the number of shelves to be used will be halved.

35 A feature of this invention is the use of a brush set arranged to contact with the terminals on the lower surface of said contact banks upon movement in a rotary direction after the completion of an odd number of steps in a vertical direction; and arranged to be moved in a rotary motion over the upper surface of the contact banks upon completion of an even number of vertical steps.

40 It is thought that the invention will be best understood from the following detailed description, reference being had to the accompanying drawings.

45 In the drawings, Figure 1 shows a perspective view of the essential operating elements of the switch, together with a suitable circuit arrangement for controlling the same;

50 Fig. 2 shows a plan view of a contact bank shelf with a brush carriage in its normal relation to said bank;

Fig. 3 is a plan view showing in what relation to one another a plurality of switches

are mounted so as to be accessible to the same contact bank; and

Fig. 4 is a detailed view of a double brush set constructed in accordance with the principles of this invention.

Referring now to Fig. 1, it will be seen 60 that there are provided a plurality of contact banks such as 10, 10' and 10''. The construction of these contact banks will be better understood by reference to Fig. 2. In Fig. 2 the unit contact bank is indicated 65 generally at 10 and is shown to be made up of a number of strips of conducting material, as indicated at 11, 12, 13, 14, 15 and 16, all suitably insulated from one another, in the manner usual in the panel type of 70 contact bank construction. These strips are arranged to run longitudinally the entire length of the shelf 10 and are provided at each switch with bent-over contact portions as 17, 18 and 19 to provide terminals for engagement with the brush set carried by arm 20. The location of the bent-over contact portions of the various strips is so arranged 75 that the contacts may be engaged successively by the brush carried by arm 20, upon 80 rotation of said arm. At 21 is indicated an arm of the switch adjacent to that controlling the arm 20. The relation of the switches and contacts may be better understood by inspection of Fig. 3, which shows a number 85 of switches in relation to a contact bank shelf.

As described in the previously mentioned application, these shelves are to be arranged one above the other, so that when the brush carriage is elevated to a desired level, the brush may then be rotated transversely of the contacts to select the desired set of contacts. Therefore in the previous arrangement it was necessary to provide as many 90 layers or shelves of multiple panel strips, each accessible to a plurality of switches, as there were groups of contacts. If it was desired that the switch should have access to ten groups of terminals, ten shelves of contacts were required in the previous arrangement. In the present arrangement, however, referring to the bank 10 in Fig. 1, it will be seen that each shelf is provided with multiple strips on its lower surface as well 100 as on its upper surface. As a result only five shelves will be needed to provide access to ten groups. As shown in Fig. 1, the con-

tacts of the first group and second group are insulated from one another in a suitable manner as indicated by the insulating strip 22.

5 The contact banks are so arranged that upon the completion of the first vertical step by shaft 23, the brushes 24, 25 and 26 will be in a position to engage the contacts on the lower side of shelf 10. Upon the completion of the second group step, the brushes 10 27, 28, 29 will be in a position to engage the contacts on the upper side of shelf 10. On the completion of the third group step, the brushes 24, 25 and 26 will be in a position 15 to engage the contacts on the lower side of shelf 10.

The mechanism for operating the brush carriage may be that of any well-known type of up and around switch and any one 20 of a number of well-known circuit arrangements may be used therewith. The switch is equally adapted for use as a selector or connector.

25 Referring now to Fig. 1, a brief description of the operation of the device as a selector switch will be given. Assuming that the subscriber whose substation is indicated at 30, desires a connection, he will remove his receiver from the switchhook, whereupon 30 his line will be extended in any desired manner to the selector whose circuits are shown in Fig. 1. In the present case, it will be assumed that the means for extending his line to the selector is a line finder, whose 35 brushes are indicated at 31, 32 and 33.

As soon as the line finder has operated, a circuit is completed from grounded battery, right-hand winding of line relay 34, side-switch wiper 35 in its first position, 40 finder brush 31, contact 36, through the loop of the calling subscriber's line, contact 37, finder brush 32, side-switch wiper 38, in its first position, left-hand winding of relay 34 to ground. Relay 34 is energized and 45 attracts its armature, completing a circuit from grounded battery, winding of slow release relay 39, armature and front contact of relay 34 to ground.

The subscriber now operates his sender, 50 indicated at 40, to cause a series of interruptions in the line circuit. Upon the first deenergization of line relay 34, a circuit is completed from grounded battery, winding of slow release magnet 41, armature and 55 front contact of relay 39, armature and back contact of relay 34 to ground. Relay 41 is energized and completes a circuit from grounded battery, winding of escape magnet 42, side-switch wiper 43, in its first position, 60 armature and front contact of relay 41 to ground. In parallel with the circuit of relay 41, a circuit is completed from grounded battery, winding of vertical stepping magnet 44, secondary off-normal contact 47, armature and front contact of relay 39, armature

and back contact of relay 34 to ground. Magnet 44 is energized and advances the brush shaft 23 one step in a vertical direction. Magnet 44 is energized in response to each interruption of the line circuit, but 70 relays 39 and 41 being slow to release, remain energized during the sending of the impulses. Upon completion of the first series of impulses, at which time the shaft 23 has been elevated to the desired contact 75 level, line relay 34 remains energized for a relatively long period of time, causing the deenergization of relay 41. The deenergization of relay 41 causes in turn the deenergization of escape magnet 42, which releases and allows the side-switch wipers to be advanced in their second position. 80

In the second position of the side switch a circuit is completed from grounded battery, contact springs 45, winding of rotary stepping magnet 46, side-switch wiper 60, in its second position, armature and front contact of relay 34 to ground. Magnet 46 attracts its armature to advance the brush shaft 23 one step in a rotary direction, thus 85 opening the contact 47 to prevent further actuation of the vertical stepping magnet 44. Magnet 46, upon attraction of its armature, interrupts its own circuit at springs 45 and deenergizes. Magnet 46 continues to interrupt its own circuit and advances the brush set over the selected contact bank until an 90 idle trunk is found. If it is assumed that the idle condition of trunks is indicated by the presence of ground potential on the test 95 terminals of said trunks, it will be observed that the escape magnet 42 is energized as soon as the brush set is positioned on the terminals of an idle trunk. This circuit for escape magnet 42 extends from grounded 100 battery, winding of escape magnet 42, side switch wiper 43, in its second position, conductor 48, test brush 26 or 29, according to whether an even or odd number of steps has 105 been taken, to ground by way of the test terminal of the idle trunk. The energization of escape magnet 42 advances the side-switch 110 wipers into their third position, thus opening the circuit of magnet 46 and bringing the brush set to rest upon the terminals of 115 an idle trunk in the selected group.

Upon completion of conversation ground will be applied to conductor 48 from the connector in the well-known manner, whereupon a circuit will be completed from 120 grounded battery, winding of release magnet 50, primary off-normal contacts 51, side-switch wiper 52, in its third position, conductor 48 to ground. Magnet 50 is energized and operates the double holding dog to 125 withdraw pawls 53 and 54 from engagement with the vertical and rotary ratchets respectively, to allow the switch to be released. It is to be observed that magnet 50 upon energization completes a locking circuit for 130

itself by way of primary off-normal contact 51, conductor 55, contacts 56 to ground. Magnet 50 therefore remains energized until the switch has been completely restored, at 5 which time the circuit of magnet 50 will be broken by the opening of off-normal contacts 51.

What is claimed is:

1. In an automatic switching device, a 10 multiple terminal bank comprising a plurality of sections arranged in superimposed tiers, each tier being provided with an upper and lower contact bearing surface, each of said surfaces comprising a separate group 15 of multiple terminal strips, switching mechanisms in operative relation to said terminal bank, and means to operate a switching mechanism to select a desired group of contacts and to select a desired contact in a selected 20 group.

2. In an automatic switching device, a multiple terminal bank comprising a plurality of sections arranged in superimposed tiers, each tier being provided with an upper and lower contact bearing surface, each of said surfaces comprising a separate group 25 of multiple terminal strips, a plurality of movable brush carriages, a brush set carried by each of said brush carriages, means to advance a brush carriage to select a desired 30 group, and means to advance said brush carriage transversely of a selected group to position its associated brush set on a desired terminal set in the selected group.

3. In an automatic switching device, a plurality of switching mechanisms, movable contacts controlled thereby, a multiple terminal bank comprising a plurality of sections arranged in superimposed tiers, each tier 40 being provided with an upper and a lower contact bearing surface, each of said surfaces comprising a plurality of terminal strips suitably insulated from one another, contact portions on said strips projecting at 45 desired intervals and in proper relation to one another, said contact portions being suitably offset for engagement with movable contacts of said switching mechanism, means to operate one of said switching mechanisms 50 to advance its movable contacts carried thereby into operative relation with one of said contact bearing surfaces to accomplish

group selection, and means to advance said movable contacts transversely of said selected surface to select a desired terminal 55 set in the selected group.

4. In an automatic switching device, a multiple terminal bank comprising a plurality of sections arranged in superimposed tiers, each tier being provided with an upper and lower contact bearing surface, each of said surfaces comprising a separate group 60 of multiple terminal strips, switching mechanisms in operative relation with said terminal bank, means to cause vertical motion 65 of a switching mechanism to select a desired group of contacts, and means to cause rotary movement of a switching mechanism to select a desired contact in a selected group.

5. In an automatic switching device, a 70 multiple contact bank comprising a plurality of unit layers placed in superimposed relation, a plurality of movable brush carriages, brushes carried thereby, means to advance a brush carriage into position to select 75 a desired group, and means to advance said brush carriage transversely of a selected group to enable the associated brushes to engage contacts in said selected group, and means to advance said brushes over contacts 80 on the lower surface of a selected layer or over contacts on the upper surface of a selected layer in accordance with whether the number of group steps taken by said carriage is odd or even.

6. In an automatic switching device, a multiple contact bank comprising a plurality of superimposed unit layers, each of said layers being provided with contact sets 90 on its upper surface and on its lower surface, vertically and rotatably movable shafts in operative relation to said contact bank, a brush carried by each of said shafts, means to selectively move a brush during vertical movement of said shaft to select a desired 95 group of contacts, and means to move said brush during rotary movement of said shaft transversely into engagement with a desired contact in the selected group.

In witness whereof I hereunto subscribe 100 my name this 16th day of November, A. D. 1917.

JAMES L. McQUARRIE.
